UNITED STATES PATENT OFFICE

170,873

TIRE

Paul N. Kaufman, Dayton, Ohio, assignor to The Dayton Rubber Company, a corporation of Ohio

Application January 2, 1953, Serial No. 22,997

Term of patent 14 years

(Cl. D90—20)

To all whom it may concern:

Be it known that I, Paul N. Kaufman, a citizen of the United States, residing at Dayton, State of Ohio, have invented a new, original, and ornamental Design for a Tire, of which the following is a specification, reference being had to the accompanying drawing, forming a part thereof.

In the drawing:

The figure is a view in perspective of a tire,
showing my new design.

I claim:

The ornamental design for a tire, substantially as shown.
